UNITED STATES PATENT OFFICE.

HARRY R. ROGERS, OF CHICAGO, ILLINOIS, ASSIGNOR TO CHICAGO CAR SEAL COMPANY, OF CHICAGO, ILLINOIS, A CORPORATION OF ILLINOIS.

SEAL.

Application filed June 18, 1921. Serial No. 478,559.

To all whom it may concern:

Be it known that I, HARRY R. ROGERS, a citizen of the United States, residing at Chicago, in the county of Cook and State of Illinois, have invented a new and useful Improvement in Seals, of which the following is a specification.

This invention relates particularly to self-locking seals, or snap-seals. Such seals are 10 adapted for use in sealing railway cars, and for other purposes.

The primary object is to provide an improved seal of this character which can be manufactured inexpensively, which is secure, 15 and which can not be tampered with, or opened, without the fact being readily noticeable.

The invention is illustrated, in its preferred embodiment, in the accompanying 20 drawing, in which—

Fig. 1 represents a perspective view of the improved seal, in its preferred embodiment, in locked condition; Fig. 2, a plan view of the seal before the end portion which 25 carries the locking member is folded on the adjoining portion; Fig. 3, a section taken as indicated at line 3 of Fig. 2; Fig. 4, a similar section of the seal in its completed condition; Fig. 5, an enlarged broken sectional 30 view of the seal in locked condition; Fig. 6, a view similar to Fig. 4, but showing a modification; and Fig. 7, a view similar to Fig. 5, but further illustrating the modification shown in Fig. 6.

Referring to the construction shown in Figs. 1 to 5, inclusive, the invention, in its preferred embodiment, comprises a shackle-strip 1 provided at one end portion with a locking stud 3. 40

The socket 2 is preferably formed integrally with the end portion 1^a of the strip 1, which is adapted to be folded back on the body of the strip. The line of folding is 45 designated 4. The strip is shown weakened at the line of folding by a line of perforations. The weakening may be effected in any desired manner, or this feature may be omitted, if desired.

The socket 2 preferably is formed by cupping the metal and punching a hole thru the cupped portion. This provides an annular embossment or rim, and this is provided with radial slits 2^a, leaving between the slits the inwardly convergent spring prongs 50 which make up the interlocking portion of the socket. Preferably, the locking prongs of the socket are not separated from each other normally. They will yield, however, to admit the flanged head of the locking 55 stud 3, after which they will engage beneath the flange and prevent withdrawal of the stud.

The body of the strip is provided on the opposite side of the line of folding 4 and a short distance therefrom with a cupped portion 5 which is adapted to accommodate the socket 2 when the end portion of the strip is folded on the body of the strip, as will be 60 understood from Fig. 4.

The socket 2 is open at both ends thereof, so that the stud 3 may extend therethru. However, when the strip is folded in the manner shown in Fig. 4, the cup 5 serves to cover one end of the socket, a sufficient space 65 being left between the bottom of the cup and the socket to admit the flange of the locking stud.

The locking stud 3 is shown as comprising a tubular member which has a reduced 70 shank extending thru a perforation in the other extremity of the strip 1, the reduced shank being clenched in the perforation by means of an operation which produces a flange 3^a. The free end of the locking stud 75 3 is provided with an external flange 3^b which may be snapped thru the socket 2 and which will thereupon be engaged by the locking prongs of the socket in the manner illustrated in Fig. 5.

It will be noted that in the finished condition of the seal, the locking stud 3 and the locking socket 2 are on the same side of the shackle-strip. The locking prongs of the socket 2, however, extend towards the opposite side of the shackle-strip, so that when the strip is folded to form its central portion into a loop, the stud 3 may be entered in 95

the socket and the flange 3^b of the locking stud will engage the prongs of the locking socket.

By observing Fig. 5, it will be noted that 5 the annular interlocking engagement between the stud 3 and the socket 2 is housed in the cup 5. A portion of the body of the strip 1 therefore serves to cover the interlocking socket at one side, while the end portion 10 of the strip which carries the stud 3 covers the base portion of the socket and prevents access from that side of the seal.

In the modification shown in Figs. 6 and 7, the shackle-strip is designated 6, and the 15 folded end portion of the strip is designated 6^a. The locking socket is designated 7; and the locking stud is designated 8. In this case, the metal in which the locking socket is formed is struck up to form an embossment 7^a; and the bottom portion of this embossment is then struck downwardly to form an inner embossment. This inner embossment has its bottom cut out to provide a perforation, and the walls of the remaining 20 portion of the embossment are slotted as indicated at 7^b, thus forming the locking socket. In view of this expedient, it is unnecessary to provide a cup similar to the cup 5 for accommodating the socket. However, it will be understood from Fig. 6 25 that it becomes desirable in this construction to mount the stud 8 in the bottom of a cup 9, which is struck in the end portion of the strip. When the seal is completed 30 and the stud interlocked with the socket, in the manner shown in Fig. 7, the embossment 9 serves as a housing to accommodate the socket 7. The socket thus is covered on one side by the embossment 9 and on the other 35 side by the body of the strip 6. In this case, as has been pointed out, it is unnecessary to cup the strip 6 in the manner described in connection with the embodiment illustrated 40 in Figs. 1 to 5, inclusive.

45 In practice, the seal is made of suitable dimensions, so that one end may be passed thru a perforation in the pin which serves to secure the hasp of the car-door. After the shackle is entered in the perforation of 50 the pin, the shackle-strip is looped in the manner shown in Fig. 1 and the stud is snapped into engagement with the socket. This may be accomplished by pressure exerted by the thumb and fingers. The locking parts are so securely interlocked and housed that it is impossible to gain access to effect separation of the interlocking parts. If it be attempted to forcibly withdraw the 55 stud from the socket, exertion of any considerable force will serve to rupture the shackle-strip before the stud can be withdrawn from the socket. A line of weakening across the shackle-strip may be employed, if desired, to insure the rupture of the strip 60

before the locking stud can be withdrawn 65 from the socket.

A modification of the invention is illustrated in my application Serial No. 478,560, filed in the United States Patent Office of even date herewith. 70

The foregoing detailed description has been given for clearness of understanding only and no unnecessary limitations should be understood therefrom, but the appended claims should be construed as broadly as 75 permissible in view of the prior art.

What I regard as new, and desire to secure by Letters Patent, is—

1. A seal comprising a shackle-strip, a locking stud carried by one end of said strip, and an open uncovered locking socket carried by the other extremity of said strip, the strip being so folded on itself as to reverse the position of the socket and thereby cover one of the open ends thereof by means 80 of the strip, said locking stud being adapted to enter the remaining open end of the socket and interlock with the socket. 85

2. A seal comprising a shackle-strip, a locking stud carried by one end of said strip, and an open locking socket formed by cupping and perforating the metal of said strip at the other extremity, the strip being so folded on itself as to reverse the position 90 of said socket and thereby cover one of the open ends of the socket with the strip, said locking stud being adapted to enter the remaining open end of the socket and interlock with the socket. 95

3. A seal comprising a shackle-strip, an 100 open locking socket carried by one extreme end of said strip, the strip being so folded on itself near said end as to reverse the position of said socket and cause one end of the socket to be closed by the body of the strip, 105 and a locking stud carried by the other end of said strip and disposed on the same side thereof as is said socket.

4. A seal comprising a shackle-strip having an open-ended socket formed in one end 110 portion thereof and having a cupped portion adjacent said end portion, the end portion being folded on the body of the strip to bring the socket within said cupped portion, and a locking stud carried by the other end 115 of the strip and disposed on the same side of the strip as is said socket.

5. A seal comprising a shackle-strip, a locking stud carried by one end of said strip, and an open locking socket formed in the 120 metal of said strip at the other extremity, the strip being so folded on itself as to reverse the position of said socket and thereby cover one of the open ends of the socket, said locking stud being adapted to enter the remaining open end of the socket and interlock with the socket, the line of folding of 125 said strip being weakened in such manner

that the strip will be ruptured at the line of folding if an effort be made to forcibly withdraw the locking stud from the socket.

6. A sealing strip adapted to form a seal, comprising a sheet-metal strip having a locking stud secured to one end thereof, the other end of said strip having the metal forming an annular cone which is slotted, said cone projecting on the same side of the strip as does said locking stud, and said strip being provided a short distance from said cone with a cup portion adapted to receive the cone when the strip is folded on itself.

HARRY R. ROGERS.
